UNITED STATES PATENT OFFICE.

STUART GWYNN, OF NEW YORK, N. Y., ASSIGNOR TO THE AMERICAN METALINE COMPANY, OF SAME PLACE.

IMPROVEMENT IN JOURNAL-BOX LININGS.

Specification forming part of Letters Patent No. 138,645, dated May 6, 1873; application filed January 29, 1873.

To all whom it may concern:

Be it known that I, STUART GWYNN, of the city, county, and State of New York, have invented a new manufacture, the same being an Improved Lining for Journal-Boxes and other rubbing surfaces, of which the following is a specification, reference being had to the accompanying drawing forming part of the same.

On the 12th day of April, 1870, certain Letters Patent of the United States were issued to me numbered from 101,862 to 101,869, inclusive, for certain compositions of matter denominated "metoline," and for the process or method of making the same, as also the offices it performs, to which reference is made.

The invention herein intended to be described and claimed relates to a special mode of applying the said several kinds of metoline, or any of them, or their equivalent, to practical use; and consists in a combination of metoline with the material, in the manner and for the purposes particularly described.

Figure 1 is a vertical sectional view of my invention, showing the first stage of its fabrication. Fig. 2 is a similar view of the same after the same has been subjected to pressure, and thus completed and rendered ready for use.

In fabricating my invention, I first take a strip or sheet of cloth of any suitable woven, knit, or felted fabric, of either vegetable or animal fiber, and spread upon the same a layer or stratum of finely-powdered metoline, or its equivalent. I then place upon this again another strip or sheet of the cloth or fabric, and then another layer or stratum of the metoline, and so on, continuing the alternate layers of metoline and of the fabric, until the desired

amount of thickness of the mass is obtained. I then subject the entire mass to severe pressure by suitably constructed rollers or presses, which pressure compresses and compacts the metoline into a solid form, and so incorporates it in and with the meshes and fiber of the fabric that it really forms one composition or substance, the fabric serving to hold the metoline in shape and position, so that it may be readily handled and cut into strips, or other desired forms, to be used in lining journal-boxes, or other surfaces designed to be subjected to friction, the metoline being a material which, in its action as such surfaces, obviates the necessity of the use of oil or any other extraneous lubricator.

In applying it to use the strips of the lining are placed, of course, with the edges or ends of the alternate layers of metoline and fabric faced upon the journals or other bearings.

With some fabrics and for some purposes, it is desirable to saturate or coat, or both, the fabric with a preparation of paraffine and caoutchouc, or other suitable composition, before spreading the metoline powder over it.

In the drawing an enlarged or magnified size of this lining is shown, in order that the invention may be more readily and conveniently perceived.

What I claim as a new manufacture is—

The composition denominated metoline, incorporated with any woven, knit, or felted fabric, of either vegetable or animal fiber, in the manner and for the purposes specified.

STUART GWYNN.
